UNITED STATES PATENT OFFICE.

WILLIAM S. CASKEY, OF INDIANAPOLIS, INDIANA.

PIPE-RACK.

1,356,040.

Specification of Letters Patent. Patented Oct. 19, 1920.

Application filed June 25, 1920. Serial No. 391,571.

To all whom it may concern:

Be it known that I, WILLIAM S. CASKEY, a citizen of the United States, and a resident of Indianapolis, county of Marion, and 5 State of Indiana, have invented a certain new and useful Pipe-Rack; and I do hereby declare that the following is a full, clear, and exact description thereof, reference being had to the accompanying drawings, in 10 which like numerals refer to like parts.

This invention relates to an improved, simple, cheap and effective means for supporting iron pipes or rods. The invention is of use for mounting heating pipes in 15 houses, factories, steamships and the like, hot houses for plants, dry kilns and the like, and is capable of use wherever it is desired to mount pipes in a manner whereby they can be readily removed.

20 The chief feature of the invention consists in providing a hanger upon which the pipe is placed and rests and a tongue or like means is punched out of a sheet of metal for supporting the hanger in proper 25 position.

Another feature of the invention consists in making the hanger double for supporting a pipe on each end thereof and the hanger being supported intermediate its ends on 30 tongues punched out of a sheet metal supporting-means. The pipes carried by the hanger on the opposite sides of the supporting-means balance each other.

Another feature of the invention consists 35 in staggering the position of the pipes carried by the double hangers by having the end of the hanger on one side of the support higher than the hanger on the opposite side thereof.

40 The full nature of the invention will be understood from the accompanying drawings and the following description and claims.

In the drawings, Figure 1 is an elevation 45 of a cross beam with a vertical support carrying a plurality of double hangers with pipes mounted in position thereon. Fig. 2 shows the upper portion of the hanger support with two hangers on an enlarged 50 scale, the lower part of the support being broken away. Fig. 3 is a section on the line 3—3 of Fig. 2. Fig. 4 is an elevation of a modified structure showing a single hanger mounted on a vertical support. Fig. 5 is a 55 section on the line 5—5 of Fig. 4.

The invention consists in a vertical plate

or bar 10 on which hangers 11 are mounted by convenient means so that said hangers will carry iron pipes 12. The supporting bar 10 is shown in Fig. 1 secured at its 60 upper end to a horizontal beam 13, but it is immaterial how said bar 10 is secured in position, so far as this invention is concerned.

The bar 10 is a metal plate which has 65 punched from it at intervals pairs of tongues 15 for receiving and supporting the hangers 16 substantially midway their ends. The hangers shown in Figs. 1, 2 and 3 are double hangers and consist of a rod with a 70 transverse intermediate portion 16 and with each end bent downward and given a semi-circular curvature at its lower end to receive the iron pipes 12. One curved lower end of the hanger is higher than the other 75 so that the pipes will be staggered in position as shown in Fig. 1.

In assembling this structure the tongues 15 are punched out so as to be longitudinal of the bar 10 and with the free ends of the 80 tongues extending upward. The hangers are put in place on the different pairs of tongues so as to rest upon the shanks of the tongues and the upper or free ends of the tongues are bent around the hanger, as 85 shown in Fig. 3, whereby it will be held firmly in position and yet be readily releasable by merely bending back the free ends of the tongues with a suitable tool, whereupon the hanger can be removed. 90 These hangers are spaced in a vertical series, one above the other, upon the supporting bar 10 so that any desired number of pipes may be mounted.

A modified form is shown in Figs. 4 and 95 5 wherein single pipe hangers 17 are mounted on the bar 10. In that instance only one tongue 15 is punched out for each hanger in which the horizontal portion of the hanger is mounted as before, and one end 100 of the hanger at 18, as shown in Fig. 5, is turned and extended through a corresponding hole in the bar 10, preferably on a level with the tongue 15. There may be any number of hangers 17 like that shown in Fig. 4, 105 mounted on one bar 10.

The invention claimed is:

1. Pipe supporting means including a metal plate support having a vertically-disposed tongue punched in the same with the 110 free end extending upwardly, and a hanger with a curved lower end for receiving a

pipe and a horizontal portion substantially placed on the shank of said tongue with the free end of the tongue curved upwardly about the hanger and the other portion of 5 the hanger being held in fixed relation with said support.

2. Pipe supporting means including a metal plate support having a pair of vertically-disposed tongues punched in the same 10 with the free ends extending upwardly, and a hanger having a curved lower end for receiving a pipe and a horizontal portion substantially placed on the shanks of said tongues with the free ends of the tongues 15 curved upwardly about the hanger.

3. Pipe supporting means including a metal plate support having a pair of vertically-disposed tongues punched in the same with the free ends extending upwardly, and 20 a double hanger having both ends bent downwardly and curved to receive pipes and the intermediate horizontal portion resting upon the shanks of said tongues and with

the tongues bent upwardly about said hanger and the hanger arranged so as to 25 have a pipe supporting end at each side of the hanger support.

4. Pipe supporting means including a metal plate support having a pair of vertically-disposed tongues punched in the same 30 with the free ends extending upwardly, and a double hanger having both ends bent downwardly and curved to receive pipes and the intermediate horizontal portion resting upon the shanks of said tongues and with 35 the tongues bent upwardly about said hanger and the hanger arranged so as to have a pipe supporting end at each side of the hanger support, one end of said hanger being on a higher level than the 40 other end, whereby the pipes carried thereby will be in staggered position with reference to each other.

In witness whereof, I have hereunto affixed my signature.

WILLIAM S. CASKEY.
